UNITED STATES PATENT OFFICE

HARRISON TYSON, OF HUNTSVILLE, OHIO

WHEELBARROW HOPPER

Application filed June 16, 1930. Serial No. 461,570.

This invention relates to wheel barrows and has for an object to provide a wheel barrow hopper having an adjustable wall for varying the cubic foot capacity of the wheel barrow.

A further object of the invention is to provide a wheel barrow hopper having a vertical wall which is adjustable longitudinally of the hopper and which is reinforced at the sides and bottom to resist dislodgment from adjusted position.

A still further object of the invention is to provide a wheel barrow hopper which is open at the rear end and is provided with a transverse wall adapted to form a closure for the rear end when desired, there being a transverse brace connecting the side walls of the hopper at the rear end thereof and forming a stop for limiting rearward movement of said transverse wall.

A still further object of the invention is to provide a wheel barrow hopper having a forwardly inclined front wall which cooperates with the transverse adjustable wall in providing means for varying the fractional cubic foot capacity of the hopper.

A still further object of the invention is to provide a simple and durable means for adjustably mounting the transverse wall in the hopper, said means comprising a guide rail carried by the bottom of the hopper and an eye carried by the slide wall and encircling the guide rail, said eye having a set screw which bears against the guide rail to lock the movable wall in various adjusted positions.

With the above and other objects in view the invention consists in certain novel details of construction and combination of parts hereinafter fully described and claimed, it being understood that various modifications may be resorted to within the scope of the appended claims without departing from the spirit or sacrificing any of the advantages of the invention.

In the accompanying drawings forming part of this specification:

Figure 1 is a longitudinal sectional view through a wheel barrow hopper constructed in accordance with my invention, the under

structure of the wheel barrow being shown by dotted lines,

Figure 2 is a plan view of my improved hopper, and

Figure 3 is a cross sectional view taken on the line 3—3 of Figure 1.

Referring now to the drawings in which like characters of reference designate similar parts in the various views, 10 designates in general the under structure of a wheel barrow 60 and 11 designates my improved hopper therefor.

The hopper is preferably formed of sheet metal and comprises outwardly sloping side walls 12, a bottom 13, and a forwardly inclined front wall 14. The rear end of the hopper is preferably open. In the present embodiment of the invention the meeting edges of the walls and bottom of the hopper are riveted together as shown at 15. Preferably a single metal strap brace 16 is riveted as shown at 17 to the side walls and front wall of the hopper and the ends 18 of the strap brace are carried across the open rear end of the hopper and riveted together, as shown at 19, to form a stop for limiting rearward movement of the sliding wall 20, which will now be described.

The sliding wall is preferably formed of sheet metal and the top, sides and bottom edges are bent horizontally and rearwardly to form flanges 21, 22 and 23 respectively, as best shown in Figure 1. These flanges stiffen the wall to resist distortion.

To prevent dislodgment of the sliding transverse wall, by now referring to Figure 3, it will be seen that a pair of straps 24 are riveted as shown at 25 to the lateral flanges of said wall and project above the top edge of the hopper. The straps are provided with downwardly extending hooks 26 which engage underneath the strap brace 16, the hooks preferably being riveted as shown at 27 to the straps. These hooks perform the function of guides to direct the sliding movement of the wall 20 and also prevent the wall being dislodged rearwardly when under load.

For securing the wall 20 in various adjusted positions longitudinally of the hopper, a guide rail 28 is riveted, as shown at 29, to the

bottom of the hopper and extends preferably along the center line of said bottom, as best shown in Figure 2. An eye 30 encircles the guide rail and is provided with an integral bracket 31 which is riveted to the wall 20, as shown at 32. The eye is provided with a set screw 33 which bears against the guide rail and serves to hold the transverse wall in various adjusted positions in the hopper, such as 5 for instance shown by full lines and also by dotted lines in Figure 2.

The cubic foot capacity of the hopper above described may be varied by adjusting the sliding transverse wall 20 longitudinally of the 15 hopper. In practice, assuming that each nine inches longitudinally of the bottom of the hopper constitutes a cubic foot capacity, measuring from the juncture of the inclined front wall rearwardly, a fractional cubic foot 20 capacity may be attained by virtue of the angle of inclination of said front wall since when the adjustable vertical wall is disposed in the hopper at the juncture of said inclined front wall with the bottom of the hopper, the volumetric content of the space between said inclined front wall, the side walls, and said vertical adjustable wall will be one-half cubic foot. Thus assuming that each cubic foot capacity of the hopper corresponds to each 9 30 inches longitudinally of the bottom, the first cubic foot capacity will be only four and one-half inches from the juncture of the bottom with said inclined front wall of the hopper.

This example is given merely as illustrative 35 of one specific embodiment of my improved measuring hopper.

Having thus described the invention, I claim:

1. A measuring wheel barrow including 40 a hopper, a slidable transverse wall therein, a longitudinal guide rail centered between the sides of the hopper and secured to the bottom of said hopper and passing through said wall at the bottom, a guide eye carried 45 by said wall and encircling said rail, a set screw carried by said eye bearing against said guide rail, and guides disposed at the upper corners of the wall slidably engaged over the top edges of the side walls of the 50 hopper.

2. A measuring wheel barrow including a hopper having an inclined front wall, a transverse vertical wall in the hopper movable toward and away from said front wall, 55 a longitudinal guide rail carried by the hopper and passing through the center of said transverse wall near the bottom edge thereof, means carried by said transverse wall for securing said wall in adjusted positions on 60 said guide rail and guides at the upper corners of the transverse wall operatively engaging the upper edges of the sides of the hopper.

3. A measuring wheel barrow including a hopper having an open rear end, a transverse brace connecting the side walls of the 65

hopper at said rear end and forming a stop, a sliding transverse wall forming a closure for said rear end and limited in rearward movement by said brace, means for securing said transverse wall in adjusted positions longitudinally of said hopper, and guides secured to the transverse wall and engaging over the outer faces of the sides of the hopper to prevent dislodgment of the wall.

4. A measuring wheel barrow including 70 a hopper, a transverse wall therein having flanges at the lateral and bottom edges for engaging the side walls and bottom of said hopper, guides secured to said lateral flanges and engaging over the outer faces of said side walls for preventing dislodgment of said transverse wall, a guide rail carried by the bottom of said hopper and extending through said transverse wall, an eye carried by said transverse wall and encircling said rail, and a set screw carried by said eye and bearing against said rail.

In testimony whereof I affix my signature.
